(57) **CLAIM**

The ornamental design for a module on a lighting fixture, as shown and described.

DESCRIPTION

FIG. 1 is an isometric view of a top, front, and left side of an ornamental design for a module on a lighting fixture;

FIG. 2 is a front elevational view of the module of FIG. 1;
FIG. 3 is a rear elevational view of the module of FIG. 1;
FIG. 4 is a left side elevational view of the module of FIG. 1;
FIG. 5 is a right side elevational view of the module of FIG. 1;
FIG. 6 is a top plan view of the module of FIG. 1;
FIG. 7 is a bottom plan view of the module of FIG. 1;
FIG. 8 is an isometric view of a bottom, front, and left side of the module of FIG. 1;
FIG. 9 is an isometric view of a top, front and left side of an ornamental design for a module on a second embodiment of a lighting fixture;
FIG. 10 is a front elevational view of the module of FIG. 9;
FIG. 11 is a rear elevational view of the module of FIG. 9;
FIG. 12 is a left side elevational view of the module of FIG. 9;
FIG. 13 is a right side elevational view of the module of FIG. 9;
FIG. 14 is a top plan view of the module of FIG. 9;
FIG. 15 is a bottom plan view of the module of FIG. 9;
FIG. 16 is an isometric view of a bottom, front, and left side of the module of FIG. 9;
FIG. 17 is an isometric view of a top, front and left side of an ornamental design for the module of FIG. 1 and FIG. 9, unattached to any lighting fixture;
FIG. 18 is a front elevational view of the module of FIG. 17;
FIG. 19 is a rear elevational view of the module of FIG. 17;
FIG. 20 is a left side elevational view of the module of FIG. 17;
FIG. 21 is a right side elevational view of the module of FIG. 17;
FIG. 22 is a top plan view of the module of FIG. 17;
FIG. 23 is a bottom plan view of the module of FIG. 17; and,
FIG. 24 is an isometric view of a bottom, front, and left side of the module of FIG. 17.
The broken lines are for the purpose of illustrating environmental structure and form no part of the claimed design.
